(80) **Hague Agreement Data**

The ornamental design for a textile thread control sensor for automatic textile, knitting or sewing machines, as shown and described.

Int. Filing Date: **Mar. 30, 2021**

DESCRIPTION

Int. Reg. No.: **DM/213837**

1. Textile thread control sensor for automatic textile, knitting or sewing machines

Int. Reg. Date: **Mar. 30, 2021**

1.1 : Perspective

Int. Reg. Pub. Date: **Apr. 30, 2021**

1.2 : Front

1.3 : Left

1.4 : Back

1.5 : Right

1.6 : Top

1.7 : Bottom

(51) **LOC (13) Cl.** **15-06**

Fig. 1.1 is a perspective view of the textile thread control sensor; fig. 1.2 is a front view thereof; fig. 1.3 is a left side view thereof; fig. 1.4 is a rear view thereof; fig. 1.5 is a right side view thereof; fig. 1.6 is a top view thereof; fig. 1.7 is a bottom view thereof.
